(57) **CLAIM**

The ornamental design for a computer cable storage, as shown and described.

DESCRIPTION

FIG. 1 is a perspective view looking downwardly at the top, back and one side of the computer cable storage. The opposite side is a mirror image of the side shown.

FIG. 2 is a back view of the computer cable storage.

FIG. 3 is a side view of the computer cable storage.

FIG. 4 is an elevational view of the front of the computer cable storage.

FIG. 5 is a top view of the computer cable storage; and,

FIG. 6 is a bottom view of the computer cable storage.
